CHILD'S BED

Max L. Gatov, 5620 Naples Canal, Long Beach, Calif.

Filed July 24, 1959, Ser. No. 56,919

Term of patent 14 years

(Cl. D5—4)

Fig. 4 is an end view of said child's bed.

I claim:

The ornamental design for a child's bed, as shown.
